Patented May 4, 1915.

Fig. 1.

Fig. 2.

Technical drawing of a rectangular frame with various dimensions and features. The frame is bounded by a thick outer line. The left side has a vertical line at 18 and a horizontal line at 6. The right side has a vertical line at 16 and a horizontal line at 6. The bottom side has a horizontal line at 15 and a vertical line at 5. The top side has a horizontal line at 20 and a vertical line at 22. The interior is divided into several sections by dashed lines. A central vertical line is at 7, and a horizontal line is at 14. Other dimensions include 25, 28, 32, 34, 21, 30, 26, 31, 24, 19, 17, 15, 13, 11, 9, 7, 5, 3, 1, and 0. There are also two small circles on the left side at 18 and 15, and a small circle on the right side at 16.

Technical drawing of a rectangular frame with various dimensions labeled:

- Top horizontal: 10, 26, 23
- Left vertical: 9, 30, 18, 22, 29
- Right vertical: 27, 16, 32, 28, 33
- Bottom horizontal: 25

UNITED STATES PATENT OFFICE.

NOBLE W. LEADBETTER, OF BICKLETON, WASHINGTON, ASSIGNOR OF ONE-THIRD TO
JENS NYGAARD, OF BICKLETON, WASHINGTON.

STIRRUP.

1,138,492.

Specification of Letters Patent.

Patented May 4, 1915.

Application filed October 31, 1914. Serial No. 869,658.

To all whom it may concern:

Be it known that I, NOBLE W. LEADBETTER, a citizen of the United States, residing at Bickleton, in the county of Klickitat 5 and State of Washington, have invented new and useful Improvements in Stirrups, of which the following is a specification.

This invention relates to stirrups of that class which are generally known as safety 10 stirrups and which are distinguished thereby that provision is made for the detachment of the foot of the rider from the stirrup in case of accident.

The invention has for its object to produce a stirrup of simple and improved construction having a hinged tread and means 15 for supporting the tread in normal position for use.

A further object of the invention is to 20 produce a tread comprising two telescoping or collapsible sections and equipped with supporting means adapted to be actuated by the collapsing or telescoping action of said sections.

With these and other ends in view which 25 will readily appear as the nature of the invention is better understood, the same consists in the improved construction and novel arrangement and combination of parts 30 which will be herinafter fully described and particularly pointed out in the claims.

In the accompanying drawing has been 35 illustrated a simple and preferred form of the invention, it being, however, understood that no limitation is necessarily made to the precise structural details therein exhibited, but that changes, alterations and modifications within the scope of the claims 40 may be resorted to when desired.

In the drawing, Figure 1 is a side view of 45 a stirrup constructed in accordance with the invention. Fig. 2 is an end view of the same. Fig. 3 is a horizontal sectional view taken on the line 3-3 in Fig. 1. Fig. 4 is a bottom plan view of a stirrup constructed 50 in accordance with the invention. Fig. 5 is an end view showing the tread detached. Fig. 6 is a sectional detail view taken on the line 6-6 in Fig. 3.

Corresponding parts in the several figures 55 are denoted by like characters of reference.

The body of the improved stirrup comprises the side members 15, 16 which are connected together and spaced apart by the top piece 17. The tread C is connected at

one edge with the side member 15 by means of hinges 18, the opposite or free edge of said tread being detachably connected with and supported by the other side members 16, as will be presently described.

The tread C may be described as consisting of a housing composed of two U-shaped members 19, 20 which are assembled together in telescopic relation, as clearly seen in Fig. 5. The member 19 is composed of top and bottom plates 21, 22 which are connected together and spaced apart by a bridge piece a. The member 20 is composed of a bottom plate 23 and a top flange 24, said plate and flange being connected together and spaced apart by a bridge piece b. The part 24 is described as a "flange" rather than a "plate", because its width and superficial area is much less than that of the parts described as plates 21, 22 and 23. In assembling the members 19 and 20 together the top plate 21 of the member 19 is slightly overlapped by the flange 24 of the member 20, while the bottom plate 22 of the member 19 extends beneath the greater portion of the bottom plate 23 of the member 20.

The hinges 18 which have been previously described as serving to connect the tread member C with the side member 15 of the stirrup are connected with the member 19 of the housing that constitutes the tread, so that the said hinges will in no wise interfere with the sliding or telescoping movement of the member 20 of said housing. Fulcrumed on the underside of the top plate 21 of the member 19 are levers 25, 26 having hooked ends 27 that project slightly beyond the free edge of the housing. The inner end of the lever 25 is connected by a link 28 with one arm of a lever 29 which is also fulcrumed on the under face of the plate 21; the other arm of the lever 29 is pivotally connected with one end of a link 30, the other end of which is pivotally connected with the under face of the flange 24 of the member 20. The inner end of the lever 26 is also pivotally connected with one end of a link 31, the other end of which is pivoted on the underside of the flange 24.

A spring 32 serves to connect the outer ends of the levers 25, 26 together, the tension of said spring also serving through the intermediate connections to move the member 20 outwardly with respect to the member 19.

Suitably formed or secured on the side member 16 of the stirrup is a supporting ledge or flange 33 serving normally to support the projecting ends of the levers 25, 26, 5 said ends forming hooks 27 that engage pins or obstructions 34 rising from the ledge or flange 33 and limiting the movement of the levers 25, 26 under the tension of the spring 32.

10 When the parts are assembled, as will be seen in the drawing, the projecting ends 27 of the levers 25, 26 will be normally supported on the ledge or flange 33, thereby supporting the tread plate or member C in position to support the foot of the rider.

Should the rider be thrown without being able to disengage his feet from the stirrup, the unusual pressure against the bridge piece b of the member 20 will slide or telescope 20 said member in an inward direction with relation to the member 19, thus actuating the levers 25, 26 through the intermediate connections against the tension of the spring 32 and thus disengaging the ends of the levers 25 from the flange 33, thereby permitting the tread member C to swing upon the hinge 18, and thus instantly releasing the foot of the rider.

As will be seen from the foregoing description, taken in connection with the drawing, I have produced a stirrup of simple and inexpensive construction by means of which accidents due to entanglement of the foot with the stirrup will be avoided. The improved device may be made in various sizes and of any desired material or combination of materials.

Having thus described the invention, what is claimed as new, is:—

40 1. In a safety stirrup, a body having side members, a tread member connected hingedly with one of the side members, and a ledge associated with the other side member; said tread member comprising telescopically related members, spring actuated levers fulcrumed on one of said members and having projecting ends adapted to be supported on the ledge, and means connecting the other ends of the levers with the other tread member constructed and arranged to actuate the

levers to disengage them from the ledge by telescoping or sliding movement of the last mentioned tread member.

2. In a safety stirrup, a body having side members, one of which is provided with a ledge, tread member hingedly connected with the other side member and having spring actuated levers with projecting ends adapted to be supported on the ledge, stop members on the ledge in the path of the projecting ends of the levers, a second tread member supported slidably or telescopically with respect to the first mentioned tread member, and means connecting the levers fulcrumed on the first mentioned tread member with the last mentioned tread member whereby sliding movement of said last mentioned tread member will operate the levers against the tension of the actuating spring.

3. In a device of the class described, a stirrup body having side members one of which is provided with a ledge, a U-shaped tread member connected hingedly with the other side member, spring actuated levers fulcrumed on the under face of the top plate of said U-shaped member and having projecting ends adapted to be supported on the ledge, a second tread member disposed telescopically with respect to the first mentioned tread member, said second tread member including a flange slightly overlapping the top plate of the first mentioned tread member, and connecting means including links connecting the spring actuated levers with the flange of the second tread member, whereby telescoping movement of said second tread member with respect to the first mentioned tread member will result in operating the levers against the tension of the actuating spring to disengage the projecting ends of said levers from the supporting ledge.

In testimony whereof I affix my signature in presence of two witnesses.

NOBLE W. LEADBETTER.
